UNITED STATES PATENT OFFICE.

MAXIMILLIAN J. DIEMMER, OF AUGUSTA, GEORGIA.

HANGER FOR INCANDESCENT LAMPS.

No. 853,444.

Specification of Letters Patent.

Patented May 14, 1907.

Application filed February 26, 1906. Serial No. 303,027.

To all whom it may concern:

Be it known that I, MAXIMILLIAN J. DIEMMER, a citizen of the United States, residing at Augusta, in the county of Richmond and State of Georgia, have invented a new and useful Hanger for Incandescent Lamps, of which the following is a specification.

This invention relates to hangers for incandescent lamps and has for its object to provide a hanger designed for attachment to a ceiling or other suitable support and by means of which the lamp may be conveniently raised or lowered, and supported at any desired height.

A further object of the invention is to provide a hanger having a spring actuated drum or roller to which is attached the flexible lamp supporting cord so that the cord may be extended to permit the positioning of the lamp in any desired portion of the room, said cord being wound upon the drum to elevate the lamp by the actuating spring.

A further object of the invention is to generally improve this class of devices so as to add to their utility, and durability as well as to reduce the cost of manufacture.

With these and other objects in view the invention consists in the construction and novel combination and arrangement of parts hereinafter fully described and illustrated in the accompanying drawings, it being understood that various changes in form, proportion and minor details of construction may be resorted to within the scope of the appended claims.

In the accompanying drawings forming a part of this specification:—Figure 1 is a longitudinal sectional view of a lamp constructed in accordance with my invention. Fig. 2 is an enlarged longitudinal sectional view. Fig. 3 is an end view of the movable contact plate or member. Fig. 4 is a similar view of a stationary contact member. Fig. 5 is a detail sectional view illustrating a modified form of the invention.

Similar numerals of reference indicate corresponding parts in all of the figures of the drawings.

The device consists of a supporting frame suspended from the ceiling or other suitable support 6 by hooks 7 engaging eyes 8 fastened to the ceiling as shown, or if desired the frame may be secured in position by screws, cleats or similar fastening devices.

Journalized in the frame 5 is a longitudinal shaft 9 to which is secured a drum or reel 10, having attached thereto a flexible supporting cord or conductor 11 carrying the lamp 12.

Extending transversely across the frame 5 at one end thereof is a diaphragm 13 defining a chamber 14 and disposed within said chamber is a spring 15 one end of which is attached to the adjacent end of the shaft 9 and the other end thereof secured to the frame 6 in any suitable manner as by rivets, bolts, or other suitable fastening devices 16, so that when the drum is rotated by exerting a downward pull on the cord 11 the spring 15 will be wound up and when the cord is released the tension of the spring will rotate the drum in the opposite direction and thereby elevate the lamp.

Secured to or formed integral with the diaphragm 13 is a ratchet wheel 17 and pivotally mounted on the adjacent end of the drum 10 are locking pawls 18 adapted to engage the teeth on the ratchet wheel 17 for locking the drum against rotation so as to support the lamp in any desired position. Secured to the opposite end of the drum 10 is a plate or disk 17' preferably formed of porcelain, gutta percha or other insulating material and to which is secured a pair of circular contact plates 19 and 20 disposed concentric with the shaft, as shown. The contact plates 19 and 20 are secured to the disk 17' by inwardly extending pins 21 to which are fastened by binding screws 21' the terminals 22 and 23 of the conductor or flexible cord 11.

Mounted on the shaft 9 and spaced from the movable contacts 19 and 20 is a stationary plate or disk 24 also formed of insulating material and having supporting brackets 25 secured thereto and in which are journalized rollers 26 adapted to engage the contact plates 19 and 20. The brackets 25 are formed with reduced extensions or shanks 27 which extend through the plate 24 and are secured thereto by binding screws 28 to which are secured the terminals 29 and 30 of a lighting circuit. Interposed between the plate 24 and the adjacent end of the frame 5 is a spring 31 the opposite ends of which bear against the plate 24 and serve to yieldably support the contact members 19 and 21. The spring 31 is preferably formed with a central enlargement 32 having an opening formed therein for the reception of the shaft 9 which serves to center the spring and pre-

vent accidental displacement of the same. Suitable guide pins 33 may also be secured to the end of the supporting frame 5 for engagement with correspondingly shaped openings 5 formed in the plate 24 whereby the latter is always maintained in parallel relation to the adjacent end of the frame.

When it is desired to lower the lamp a longitudinal pull is exerted on the flexible conductor 11 which unwinds the conductor from the drum and at the same time contracts the spring 15, the lamp being supported in adjustable position by engagement of the locking pawls 18 with the teeth on the ratchet teeth 17. In order to elevate the lamp it is merely necessary to exert a slight longitudinal pull or jerk on the conductor which releases the locking pawls 18, when the coiled spring 15 will rotate the drum and automatically wind the cord or conductor thereon and elevate the lamp. It will thus be seen that when the lamp is either raised or lowered the current will flow from the terminal 30 through the shank 27 and contact roller to the concentric plate 20 and thence through the pin 21 and terminal 23 to the lamp, the circuit being completed through the terminal 22, plate 19 and adjacent contact roller, to the shank 27 of said roller and thence to the terminal 29 of the lighting circuit. In order to cover and protect the supporting frame and operating mechanism a housing or casing 34 is secured in any suitable manner to the ceiling or support 6, said casing being provided with an opening 35 for the reception of the flexible conductor 11, there being a similar opening 36 formed in the bottom of the supporting frame and preferably disposed in alignment with the opening 35 as shown.

From the foregoing description it is thought that the construction and operation of the devices will be readily understood by those skilled in the art, and further description thereof is deemed unnecessary.

In Fig. 5 of the drawings there is illustrated a modified form of the invention in which the guide pins are dispensed with and a coiled spring 35 is employed for yieldably supporting the rollers in engagement with the contact plates.

If desired the drum may be geared up in any suitable manner so as to increase the speed of the same and the several parts plated, japanned or otherwise ornamented to give the hanger an attractive appearance.

Having thus described the invention what is claimed is:

1. In a device of the class described, a supporting frame, a spring actuated drum journaled in the frame, a movable contact secured to and mounted for rotation with the drum, a stationary contact adapted to engage the movable contact, a flexible conductor carried by the drum and having its terminals connected with the movable contact,

and means independent of the contacts for yieldably supporting the stationary contact in engagement with the movable contact.

2. In a device of the class described, a supporting frame, a spring actuated drum journaled in the frame and provided at one end thereof with a plurality of contacts mounted for rotation with the drum, a plate provided with contact rollers adapted to engage removable contacts, a spring for yieldably supporting the rollers in engagement with the movable contacts, and a flexible conductor carried by the drum and having its terminals connected to the movable contacts.

3. In a device of the class described, a supporting frame, a spring actuated drum journaled in the frame and having a plurality of concentric plates secured thereto and forming contacts, a stationary plate spaced from the adjacent end of the drum and provided with contact rollers adapted to engage concentric plates, means for yieldably supporting the rollers in engagement with the contact plates, and a flexible conductor, the terminals of which are connected to concentric contact plates.

4. In a device of the class described, a supporting frame, a spring actuated drum journaled in the frame and having a plurality of concentric plates secured to one end thereof and forming contacts, a disk spaced from the adjacent end of the drum, rollers journaled on disk for engagement with the contact plates and provided with threaded shanks, screws engaging the threads on said shanks, a spring interposed between the disk and the adjacent end of the frame, and a flexible conductor the terminals of which are connected to the contact plates.

5. In a device of the class described, a supporting frame, a spring actuated drum journaled in the frame and having a plurality of concentric plates secured to one end thereof and forming contacts, a disk spaced from the adjacent end of the drum and provided with guide openings, rollers journaled on the disk and adapted to bear against the contacts, pins secured to the frame and engaging the guide openings, a spring interposed between the disk and the adjacent end of the frame for yieldably supporting the roller in engagement with contacts, and a flexible conductor the terminals of which are connected to the contact plates.

6. In a device of the class described, a supporting frame, a shaft mounted for rotation on the frame, a drum secured to the shaft, a diaphragm extended across one end of the frame and having a ratchet wheel secured thereto, pawls pivoted to the adjacent end of the drum and adapted to engage the ratchet wheel, a spring interposed between the diaphragm and the adjacent end of the frame, and having one end thereof secured to the shaft and the opposite end thereof secured to

the frame, a plurality of concentric plates secured to the opposite end of the drum and forming contacts, a disk spaced from one end of the frame and provided with contact rollers adapted to bear against the concentric plates, a spring yieldably supporting the rollers in engagement with the contact plates, and a flexible conductor the terminals of which are connected to said contacts.

10 7. In a device of the class described, a supporting frame, a shaft journaled in the frame, a spring actuated drum carried by the shaft and having one end thereof provided with concentric contact plates movable with the drum, a disk spaced from one end of the

frame and provided with contact rollers for engagement with the contact plates, and a spring interposed between the disk and the adjacent end of the frame, and provided with a central perforated enlargement for the reception of the shaft, said spring being adapted to yieldably support the rollers in engagement with the contact plates. 20

In testimony that I claim the foregoing as my own, I have hereto affixed my signature in 25 the presence of two witnesses.

MAXIMILLIAN J. DIEMMER.
